TOILET CASE OR THE LIKE

Joseph P. Donahue, Niagara Falls, and Eric K. Lotthammer, Jamaica, N. Y.; said Lotthammer assignor to said Donahue

Application May 5, 1951, Serial No. 15,077

Term of patent 7 years

(Cl. D86—10)

To all whom it may concern:

Be it known that we, Joseph P. Donahue, a citizen of the United States, residing at 614 76 Street, Niagara Falls, New York, and Eric K. Lotthammer, a citizen of the United States, residing at 166-04 81st Avenue, Jamaica, New York, have invented a new, original, and ornamental Design for a Toilet Case or the like, of which the following is a specification, reference being had to the accompanying drawing, constituting a part hereof.

Fig. 1 is a perspective view of the toilet case or the like, according to our new design with the top rolled back.

Fig. 2 is a perspective view of the design with the top rolled back and with the tray lifted.

Fig. 3 is a top perspective view of the design with the tray lifted up to expose the mirror.

Fig. 4 is a perspective view of the case showing the lifting strap and with the cover in the closed position and latched.

We claim:

The ornamental design for a toilet case or the like, substantially as shown.

JOSEPH P. DONAHUE.
ERIC K. LOTTHAMMER.
